UNITED STATES PATENT OFFICE.

FREDERICK M. SCHMIDT, OF BROOKLYN, NEW YORK, ASSIGNOR TO SELF WINDING CLOCK COMPANY, OF BROOKLYN, NEW YORK, A CORPORATION OF NEW YORK.

SELF-WINDING CLOCK.

1,189,630.

Specification of Letters Patent.

Patented July 4, 1916.

Application filed February 27, 1915. Serial No. 10,967.

To all whom it may concern:

Be it known that I, FREDERICK M. SCHMIDT, a citizen of the United States, residing at Brooklyn, in the county of Kings and State of New York, have invented certain new and useful Improvements in Self-Winding Clocks, of which the following is a full and clear specification.

This invention relates to self-winding 10 clocks and has for its primary object to provide improved means for controlling the operation of the same.

In the preferred embodiment of my invention, I employ a main spring for driving 15 the clock, an electro-responsive device for winding the spring and an electric circuit for energizing said electro-responsive device, said circuit including an automatic make and break device which is operated 20 partly by the main spring and partly by said electro-responsive device.

The details of invention will appear in the specification and be pointed out in the appended claims, reference being had to the 25 accompanying drawings, in which my invention is exemplified, and in which,

Figure 1 is a front elevation of a self-winding clock, provided with my improvements, parts being omitted and parts broken away; Fig. 2 is a section on the line II-II, Fig. 3, showing the automatic device for controlling the operation of the electro-responsive means for winding the clock, parts being broken away to show connections in 35 the rear thereof; Fig. 3 is a plan view of the clock; Fig. 4 is a side elevation corresponding to Fig. 1, parts being omitted; Fig. 5 is a fragmentary front elevation of the winding mechanism; Fig. 6 is a rear elevation 40 of the circuit controlling mechanism showing the parts in circuit-closing position, parts being broken away and parts shown in section.

In order that my invention may be more 45 readily understood, the description is confined to the preferred embodiment. An inspection of the claims however, will make it clear that the invention is not limited to the particular construction and arrangement of 50 parts shown on the drawings.

Referring more particularly to the drawings, a pair of spaced frames 1 serve to journal a main spring shaft 2, which carries the main spring 3 (see Fig. 5). A winding 55 ratchet 4 is suitably arranged to be engaged

by a pawl 5, pivoted on a pin 6, which is carried by a plate 7, oscillatably mounted upon the shaft 2. A link 8 has its upper end pivotally connected by a pin 9 to the oscillating plate 7. The lower end of the link 8 is pivotally connected by a pin 10 (see Fig. 1) with the upper end of a plunger 11 which is normally retained in raised position by a spring 12. A suitable electro-responsive device for operating the plunger 11 may be provided by a solenoid 13, which is mounted in a frame 14, which suspends from the spaced frames 1. Keyed to the spring shaft 2 is a gear 15; which meshes with a pinion 16 keyed to the minute hand shaft 17. A larger gear 18 which is also keyed to the shaft 17 meshes with a pinion 19 on a spindle 20, which also carries a gear 21, which is controlled by a suitable escapement (not shown in the drawings). Loosely mounted on the minute hand shaft 17 is a double cam embodying the lobes 22, 23 each of said lobes being of sufficient breadth to simultaneously engage a pair of parallelly arranged spring arms 24 and 25, which constitute portions of an automatic make and break device presently to be described. The spring arm 25 is shorter than the spring arm 24, as shown in Fig. 3 and as shown in Fig. 2, has an upwardly deflected portion 26 which is connected by a leaf spring 27, to a fixed plate 28 rigidly mounted upon an insulating strip 29. The outer end of the fixed plate 28 is provided with a binding post 30, to which is attached a wire 31. The spring arm 24 is connected by a leaf spring 32, with a fixed plate 33, which is mounted on an insulating strip 34, and provided with a binding post 35, to which is attached another wire 36. As shown in Fig. 1, the wire 36 is connected to one end of the solenoid 13, the other end of said solenoid being connected by a wire 37 to a binding post 38, to which is also connected a lead wire 39. A pair of overhanging current conducting arms 40 and 41 are suitably connected to the spring 27 and carry a pair of contacts 42, which are normally held spaced from a pair of similar contacts 43, carried by the arm 24 when the cam arms 24 and 25 are on a level with each other. When however, the cam arm 25 drops from the high point of a cam lobe while the cam arm 24 remains on said high point, contacts 42 and 43 are

100
105
110

brought together. A fixed abutment 44, for the cam arms 24 and 25 is mounted on the strip 45. It will be seen that whenever the contacts 42 are forced against the contacts 43, a circuit will be closed which includes a source of power (not shown on the drawings) wire 31, binding post 30, plate 28, leaf spring 27, arms 40, 41 contacts 42, contacts 43, cam arm 24, leaf spring 32, fixed plate 33, binding post 35, wire 36, solenoid 13, wire 37, binding post 38, and wire 39, back to battery or other source of power.

In the preferred embodiment of my invention shown on the drawings, it was desired to have the cam operated by the clock train in order to energize the winding solenoid at predetermined intervals during which the clock was running. At the same time in order to reduce the consumption of current to a minimum, it is desirable to have the winding movement break the circuit. In order to carry out the former object, the minute hand shaft 17 is provided with a radially projecting pin 46 which is adapted to engage a pin 47 projecting from lateral face of the cam 22, 23; after each operation of the winding mechanism, the pin 47 carried by said cam will usually be some angular distance in advance of the pin 46 which is driven by the clock-work. Projecting from the opposite face of said cam is a second pin 48 which at times engages or is engaged by a radial finger 49' carried by a disk-like plate 49 which is oscillatable independently of the shaft 17.

Rigid with the ratchet 4 by the aid of which the main spring 3 is wound, is a gear, 65, (see Fig. 2) which meshes with a pinion 66, said pinion being freely journaled on the shaft 17. The pinion 66 is provided with a laterally projecting pin 67 which is oscillatable in an arcuate recess 68 in the disk or plate 49, being thereby adapted at the end of each winding movement to rotate the disk or plate 49 after taking up the lost motion through said recess which permits a full stroke movement of the plunger 11 before the energizing current is cut off. A pivotally mounted dog 51 is held against the winding ratchet 4 by means of a leaf spring 52 (see Fig. 5). As shown in Fig. 1, a blade 60 mounted on a fixed pedestal 61 serves to limit the upward movement of the plunger 11.

The operation of the device will now be readily understood and briefly related as follows: After each winding operation, the contacts 42 are normally spaced from the contacts 43. As the minute hand shaft 17 is rotated by the main spring 3, under the control of the escapement mechanism (not shown), lost motion between pins 46 and 47 is first taken up after which the cam comprising lobes 22 and 23, will simultaneously raise the spring arms 24 and 25, without per-

mitting contacts 42 to engage contacts 43. By reason, however, of the unequal lengths of the spring arms 24 and 25, the arm 25 will drop from the outer run of the cam prior to the longer arm 24. The effect of this is to permit the leaf spring 27 to draw the contacts 42 down on to the contacts 43, thus closing the circuit above referred to. This energizes the solenoid 13 and draws the plunger 11 downward, thus imparting a winding movement to the main spring 3. Inasmuch as the gear 65 partakes of this winding movement, the pinion 66 is caused to rotate, thus causing the pin 67 to traverse the arcuate slot 68 and to rotate the disk or plate 49. By the movement of said disk or plate 49, the finger 49' is brought into engagement with the pin 48 which imparts an additional rotary movement to the cam sufficient to release the cam arm 24 which breaks the circuit. According to the showing made in Fig. 6, said pin 67 will revolve the finger 49' in a counter clockwise direction for approximately one entire revolution. In this manner the relatively slow clockwork brings about the energization of the circuit which operates plunger 11 while the plunger automatically effects the interruption of the current which energizes the solenoid that draws it down. Current consumption is thereby reduced to a minimum. By means of the overhanging spring arms 40 and 41, the contacts 42 are forced evenly against the contacts 43 and provide a large area of contact. On the other hand, the sudden drops in the cam 22, 23, serve, to effect a sudden separation of the contacts 42 from the contacts 43, thus imparting a desirable snap action to the circuit breaking movement.

I claim:

1. In a self-winding clock, a main spring, electromagnetic means for winding said spring, an energizing circuit for said electromagnetic means, and means for making and breaking said circuit, said means including a clock shaft driven by said main spring, a cam loosely mounted on said clock shaft and having oppositely projecting pins, a radially projecting pin carried by said clock shaft for engaging one of the pins on said cam, a lost motion disk loosely mounted on said shaft and adapted to engage the other pin on said cam, and means operated by said electromagnetic means for rotating said disk.

2. In a self-winding clock, a main spring shaft, a main spring having one end attached thereto, a clock shaft geared to said main spring shaft, an electroresponsive device suitably connected to the other end of said spring to wind it upon the spring shaft, an electric circuit for energizing said electroresponsive device, a cam loosely mounted on said clock shaft for controlling said cir-

- cuit, means driven by said clock shaft for engaging said cam, and means driven by said electroresponsive device independently of said shaft for engaging said cam, the last 5 said means including a laterally projecting pin carried by said cam, and a member loosely mounted on the clock shaft and having lost motion connection with said electroresponsive device.
- 10 3. In a self-winding clock, a main spring shaft, a main spring having one end attached thereto, a clock shaft geared to said main spring shaft, an electroresponsive device suitably connected to the other end of 15 said spring to wind it upon the spring shaft, an electric circuit for energizing said electroresponsive device, a cam loosely mounted on said clock shaft for controlling said circuit, means driven by said clock shaft for engaging said cam, and means 20 driven by said electroresponsive device independently of said shaft for engaging said cam, the last said means including a plate movably mounted on said clock shaft and having lost motion connection with said plate, said member being driven by said electroresponsive means. 25

FREDERICK M. SCHMIDT.
